UNITED STATES PATENT OFFICE

JOSEPH SAMUELS NURNBERGER, OF ST. ALBANS, WEST VIRGINIA

VISE

Application filed January 11, 1932. Serial No. 585,987.

This invention relates to a vise designed more especially for use in the assembly of leaf springs such as used on automobiles and other vehicles, one of the objects being to provide a device which can be compactly stored, easily assembled for use and can be employed as an ordinary vise for gripping pipes, angular structures and special work, it being possible to change the jaws quickly.

Another object is to provide a means whereby removable supplemental jaws can interlock with their holders and thus be held against accidental displacement.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred forms of the invention have been shown.

In said drawings:

Figure 1 is a plan view of the vise set up for use in assembling laminated springs.

Figure 2 is a section on line 2-2, Figure 1, supplemental jaws being shown connected to the main jaws.

Figure 3 is a section on line 3-3, Figure 2.

Figure 4 is a rear elevation of the removable supplemental jaw shown in Figure 2.

Figure 5 is a side elevation thereof.

Figure 6 is a rear elevation of the supplemental jaw.

Figure 7 is a side elevation thereof.

Figure 8 is a plan view of a supplemental jaw designed for special work.

Figure 9 is a side elevation of a supplemental jaw for use in converting the structure to a pipe holding vise, portions being broken away.

Referring to the figures by characters of reference 1 designates a box-like base the flat top of which is provided with an elongated central opening 2. Side flanges 3 extend from the top of the base and constitute con-

tinuations thereof and each of these flanges is cut away near one end to form spaces 4 whereby it is possible to assemble the main movable jaw with the base as hereinafter explained.

A feed screw 5 is arranged longitudinally of the base below the opening 2 and is journaled at its ends in the end walls of the base as indicated at 6. One end of the screw projects outwardly from the base and has a head 7 with flat sides 8 straddled by the forked end 9 of a crank 10 whereby it is possible readily to rotate the head and screw. A collar 11 is secured to the screw and one wall of the base extends between this collar and head 7 so that the screw is thus held against longitudinal movement although free to rotate.

Formed on the base at one end of the opening 2 is a stationary jaw 12 the middle portion of which is cut away as at 13. This jaw is provided on its active face with ribs 14 extending from the top to the bottom thereof and reinforcing webs 15 are provided between the opposite face of the jaw and the base 1.

A movable jaw is supported detachably by the base and has been indicated at 16. This movable jaw is formed with a bottom 17 adapted to rest upon base 1. This bottom extends beyond the side flanges 3 and has depending inturned flanges 18 adapted to straddle flanges 3 and thus hold jaw 16 assembled with the base. By moving the jaw 16 to a point between the cut away portions 4, it becomes possible to lift the jaw from the base.

Ribs 19 are formed on the active face of jaw 16 and extend from the top thereof to points slightly elevated above the base. The middle portion of the jaw is cut away as indicated at 20 and reinforcing webs 21 are formed integral with the jaw and its bottom portion 17. Formed integral with the bottom portion 17 is a depending block 22 having a bore 23 extending therethrough for the reception of screw 5. This bore is of greater diameter than the screw and is intersected by a transverse slot 24 formed within and opening through the sides of the block 22. A nut 25

is insertible transversely into the slot and its height is less than the height of the slot, thus the nut and the block 22 can have sliding relative movement in a vertical direction.

5 When it is desired to use this vise for the purpose of assembling a laminated spring the jaw 16 is placed on the base so that its in-turned flanges 18 will enter the spaces 4. Said jaw can then be moved longitudinally on 10 the base and will interlock therewith. The nut 25 having been inserted laterally into slot 24 the screw 5 is inserted into the base and onto the end openings provided therefor. It is also inserted through sleeve 11 and 15 bore 23 and screwed through the nut 25 until one end of the feed screw becomes seated in the other end of the base. Sleeve 11 is then adjusted against the inner side of the base and secured to the screw so that it, in cooperation 20 with head 7 will hold the screw against longitudinal movement.

The spring or other work to which the device is adapted to be placed between the jaws 12 and 16 and where it will be held 25 against lateral displacement by the ribs 14 and 19. By rotating the screw the jaw 16 will be shifted relative to jaw 12 thereby placing the spring under the desired compression or releasing it as desired.

30 This device can be used as an ordinary vise by combining supplemental jaws with the main jaws. In Figures 3, 4, and 5, a movable supplemental jaw has been shown. This jaw 26 is formed in its back face with recesses 27 one or more of which are adapted to receive the ribs 19 while at the same time the jaw will thrust firmly against the main jaw 16. A lug 28 is formed on the back of the supplemental jaw 26 and has a screw threaded 35 40 stud 29 projecting therefrom which is adapted to extend through a clamp 30.

After the supplemental jaw has been applied to the main jaw at which time it extends both under and over the ribs 19, as 45 shown in Figure 2, the clamp 30 is placed between the ribs 21 and on stud 29. Wing nut 31 or the like is then screwed onto the stud 29 so as to bind the clamp 30 upon the jaw 16 and thereby hold the supplemental 50 jaw securely in position. Small centering wings 32 can be extended downwardly from jaw 26 to facilitate its assembly with the main jaw.

The other supplemental jaw 33 is adapted 55 to be assembled with the main jaw 12 and has recesses 34 in its back face one or more of which are adapted to receive the ribs 14. Jaw 33 not only bears against the ribs 14 and jaw 12 but also laps the top of the jaw 60 65 12 and has a flange 35 which extends under said jaw. Lug 36 is formed integral with jaw 33 and has a screw threaded stud 37 for engagement by a clamp 38. This clamp is adapted to bear against the jaw 12 between webs 15 and by means of a nut 39 en-

gaging stud 37 the clamp can be pressed against jaw 12 to hold the jaws 33 and 12 together firmly.

Where supplemental jaws, such as shown in Figures 3-7, are employed the vise can be used for holding angular structures in the same manner as an ordinary vise. However, by forming both supplemental jaws with flanges 40 on their active faces serrated plates 41 can be fastened to these flanges and the vise thus used for gripping round objects such as pipes. One of the supplemental jaws thus constructed has been shown in Figure 9.

Supplemental jaws of other forms for holding special work can be used with this structure. For example, and as shown in Figure 8, the supplemental jaw 42 can be made with an angular recess 43 in its working face, this recess being lined with leather or other soft material indicated at 44. A jaw of this construction can be used for holding pistons and the like.

When the device herein described is not in use or is to be stored or transported, the sliding jaw can be detached readily from the base and the screw can be removed as will be obvious. By pivotally connecting the crank to the screw it can be swung to any desired angle to facilitate packing. Openings 45 can be provided in the base to receive screws or the like used for fastening it to a bench.

What is claimed is:

1. A vise including a slotted base, a feed screw therein, fixed and movable jaws on the base, an operative connection between the screw and movable jaw, a rib on one face of each jaw, supplemental jaws bearing against and adapted to receive the ribs, said ribs constituting means for holding the supplemental jaws against lateral displacement, and means carried by the supplemental jaws for clamping them to the main jaws.

2. A vise including a slotted base, a feed screw therein, fixed and movable jaws on the base, an operative connection between the screw and movable jaw, a rib on one face of each jaw, supplemental jaws bearing against and adapted to receive the ribs, said ribs constituting means for holding the supplemental jaws against lateral displacement, means carried by the supplemental jaws for clamping them to the main jaws, and means on the supplemental jaws for extending over and under the ribs on the main jaws to interlock therewith.

In testimony that I claim the foregoing as my own, I have hereto affixed my signature.

JOSEPH SAMUELS NURNBERGER.
